DIRIGIBLE SKI SLED

Charles G. Van Tress, 4830 Fauna St., Montclair, Calif.,
and Jerald B. Wilken, 755 Lasena Court, Pomona,
Calif.

Filed Oct. 9, 1962, Ser. No. 72,253

Term of patent 14 years

(Cl. D34—15)

FIG. 1.

FIG. 2.

FIG. 3.

FIG. 1 is a top plan view of the dirigible ski sled showing our new design.

FIG. 2 is a side elevational view thereof, and

FIG. 3 is a rear elevational view.

The characteristic features of the present design have been shown by means of full lines in the drawing.

We claim:

The ornamental design for a dirigible ski sled, as shown and described.
